UNITED STATES PATENT OFFICE.

THOMAS JEFFERSON FOSTER, OF SHENANDOAH, PENNSYLVANIA, ASSIGNOR
TO GEORGE W. GAIL, ERNST SCHMEISSER, AND CHRISTIAN AX, OF
BALTIMORE, MARYLAND.

SQUIB, MATCH, AND TOUCH-PAPER SAFETY-BOX.

SPECIFICATION forming part of Letters Patent No. 311,183, dated January 27, 1885.

Application filed October 25, 1884. (No model.)

To all whom it may concern:

Be it known that I, THOMAS J. FOSTER, a citizen of the United States, residing at Shenandoah, in the county of Schuylkill and State 5 of Pennsylvania, have invented certain new and useful Improvements in Combined Squib, Match, and Touch-Paper Safety-Boxes; and I do hereby declare the following to be a full, clear, and exact description of the invention, 10 such as will enable others skilled in the art to which it appertains to make and use the same.

My invention relates to miners' squib, match, and touch-paper safety-boxes, and has for its object to provide a box for miners' use which 15 shall be separated into compartments adapted to receive squibs, matches, and touch-paper, and effectually protect the same from dampness in the mines, the whole being inclosed within a small compass and in convenient 20 form to be carried in the pocket. I accomplish this object in the manner hereinafter described, reference being had to the accompanying drawings, and letters of reference marked thereon, which form a part of this 25 specification.

Like letters refer to similar parts throughout the several views.

In the accompanying drawings, Figure 1 is a perspective view of my combined squib, 30 match, and touch-paper safety-box with the top removed; Fig. 2, a longitudinal section of the same, showing its interior construction. Fig. 3 is a top view of one of the covers of the box, showing the corrugated surface used for 35 lighting matches. Fig. 4 is a modification.

The form of the box is preferably elliptical in cross-section, as shown in Fig. 1, as this form is found to be more convenient for pocket use. It is preferably made of metal, though wood, 40 rubber, or other suitable material may be employed, if desired. It is provided at its ends with covers B and B', one of the covers, B', having its top corrugated or rough, thus affording a convenience for lighting matches.

45 The box is provided with an interior case,

a, which may be of the form shown, and should extend through the entire length of the box, having the compartment or space *b* surrounding the same. The end of the case *a* is soldered or otherwise secured to the bottom *e* 50 of the box, through which it passes. The compartments *c* and *d* are formed within the interior case by means of the partitions *f* and *f'*, placed at suitable distances within the same. The compartment *b* surrounding the interior 55 case is intended to contain the squibs or fuses, the compartment *c* matches, and the compartment *d* at the opposite end of the box is adapted to contain a package or roll of touch-paper.

I do not wish to confine myself to the particular form of cover described. Hinged covers provided with springs for opening and catches for securing the same when closed, such as I have shown in Fig. 4 of the drawings, 60 65 may be substituted for the cover adapted to fit over the ends of the box.

A box of the form described will afford miners an opportunity of packing their squibs, matches, and touch-paper within small compass, so that the same will be readily accessible when desired for use.

The box would be both inexpensive and durable, and if properly constructed would prevent the contents from injury from dampness.

Having thus described my invention, what I claim as new, and desire to secure by Letters Patent, is—

A box for miners' use having a compartment at one end for matches, a separate compartment surrounding the same for squibs, and a compartment at the opposite end of the box for touch-paper.

In testimony whereof I affix my signature in 85 presence of two witnesses.

THOMAS JEFFERSON FOSTER.
